TUBE CLEANING HEAD

Morril B. Spaulding, Habana, Cuba

Application March 27, 1942, Serial No. 436,503

3 Claims. (Cl. 15—104.09)

The present invention relates to improvements in tube cleaning heads for removing scale and other incrustations from the inner surfaces of the tubes of boilers, heaters, condensers, evaporators and similar apparatus, and it is more particularly applicable to the cleaning of tubes which are composed of relatively soft metal, such as copper or bronze.

The primary object of the invention is to provide a novel and improved tube cleaning head which is capable not only of removing rapidly and efficiently relatively hard and dense scale or incrustations from the interior surfaces of relatively soft metal tubes but is capable of doing so without shaving, striating or otherwise damaging the metal and of imparting a burnished finish to the interior surface of the tube, so that no pits or other irregularities will be left in the metal surface of the tube to promote the subsequent accumulation of scale or other deposits thereon.

Tube cleaning heads having radial blades pressed outwardly to engage the inner walls of tubes and effect a cleaning action by rotation of the head have been previously proposed, but such heads have not proven entirely satisfactory. In such previously proposed heads of this type which I am aware of, no means has been provided for centering the head in the tube or gauging the extent of outward movement of the blades, so that the blades had a tendency to exert undue pressure at one side of the tube, and of shaving, striating, and otherwise damaging the metal of the tube, especially when the tube is composed of copper or similar relatively soft metal.

The present invention provides an improved cleaning head of this type which overcomes these objections and produces novel and improved results. According to the present invention, the head is provided with members which serve to center the head in the tube and to control the action of the blades, whereby the blades are caused to act on the inner surface of the tube uniformly around its circumference, thus effecting thorough cleaning of the tube without undue pressure against any one side of the tube, such as would shave the metal therefrom, and the cutting edges of the blades are maintained parallel to the tube walls, thus insuring efficient action of the blades throughout their lengths and avoiding striating the metal of the tube, and by controlling the action of the blades and centering them within the tube, a burnishing action is produced on the inner tube surface which closes the pores of the metal and produces a smooth sur-

face which minimizes adhesion of scale or other deposits thereon.

The preferred embodiment of the invention is shown in the accompanying drawing wherein—

5 Figure 1 is a side elevation of the improved tube cleaning head;

Figure 2 is a central longitudinal section thereof;

Figure 3 is a transverse section taken on the 10 line 3—3 in Fig. 2; and

Figure 4 is a view of the body of the head with the blades removed.

Similar parts are designated by the same reference characters in the different figures.

15 The improved tube cleaning head, in its preferred construction, comprises a body 1 which is in the form of a solid cylinder having a suitable number, at least three, of radial slots 2 formed therein, four of these slots being shown in the

20 present instance. These slots extend in parallelism to the central or longitudinal axis of the head and are spaced equidistantly circumferentially thereof. A blade 3 is fitted loosely in each of these slots, these blades being freely movable

25 radially in their slots, the outer edge of each blade being bevelled to provide a relatively sharp scraping or cleaning edge 4 extending throughout its length. The body of the head and the blades are composed of appropriate metal, and the body

30 may vary in diameter and length, and the blades may vary in length, radial width and thickness according to the inside diameters of the different tubes to be cleaned.

Inward movement of the blades is limited by 35 the inner ends of the slots formed in the solid body of the head, and outward movement of the blades is limited by reduced extensions 5 projecting from the ends of the blades and cooperating with limiting means on the head. Such limiting

40 means comprises, in the present instance, a disk 6 which is threaded removably on a screw-threaded stem 7 which projects axially from one end of the head and has an annular counter-bore 8 formed therein to receive the extensions 5 on the

45 blades adjacent to one end of the head, and a collar 9 which is threaded removably on a screw-threaded shank 10 which extends axially from the other end of the head, said collar having an annular counter-bore 11 to receive the extensions 5 on the blades adjacent to that end of the head.

The blades may be inserted into or removed from 50 their slots while one or both the disk 6 and collar 9 are unscrewed or removed, and when these parts are screwed into their places, as shown in Fig. 2, they permit radial movements of the blades in

their slots but limit their outward movement and prevent displacement from their slots under the centrifugal force developed in the blades by the rotation of the head.

According to the present invention, the head is provided with means for centering it in the tube undergoing cleaning, and for controlling the action of the blades thereon. The disk 6 serves, in the present instance, as such centering and controlling means at one end of the head, and a similar disk 12 serves as such centering and controlling means at the other end of the head, the disk 12 having a sleeve 13 thereon which is internally threaded to screw onto the threaded shank 10 and abut against the collar 9 to lock it in place and provide a driving connection for the head, this disk 12 having a screw-threaded stem 14 projecting therefrom for the attachment of a universal joint 15 which may be connected to a rotary steam or air motor for rotating the cleaning head at an appropriate speed.

The disks 6 and 12 are each of generally circular form and of a diameter about $\frac{3}{4}$ of an inch less than the inside diameter of the tube to be cleaned, such as the tube designated X in Figs. 2 and 3, and the depth of the slots 2 and the radial width of the blades 3 are so proportioned that the diameter of said disks is greater than that of the circle in which the outer edges of the blades lie when the blades are retracted to their innermost positions, or rest against the inner ends of their radial slots. This feature of the present invention prevents a solid bearing of the blades against any one side of the tube being cleaned, since each blade can move into its slot so that its outer edge is within the peripheries of the disks at the respective sides thereof, although all of the blades will float in a circle, the diameter of which is greater than that of the disks 6 and 12. As these disks are of a diameter nearly equal to the inside diameter of the tube being cleaned, they will center the head in the tube with its axis parallel to that of the tube, so that the outer bevelled edges of the blades will be held parallel to the inside wall of the tube and will therefore act thereon uniformly throughout their length. The peripheries of the disks 6 and 12 are provided with circumferentially spaced recesses 16 and 17 respectively to afford free passageways through which air exhausted from the air motor may flow past the head and thus carry away the particles of scale or incrustation removed from the tube by the cleaning head, as when the head is employed for dry cleaning of tubes or for the flow of liquid which will wash away such particles when the head is employed for wet cleaning. The projections 18 and 19 intervening the recesses provide ample bearing surfaces for the smooth rotation of the head in the tube.

In using a cleaning head constructed as hereinbefore described, a head of a size appropriate for the inside diameter of the tube to be cleaned is connected by the universal joint 15 to an air motor or other suitable operating means and inserted into one end of the tube and driven at a speed of preferably about 6500 revolutions per minute. While the head is being so driven, it is advanced to the other end of the tube, the head removing the scale or incrustation as it advances, after which the head is withdrawn from the tube. By virtue of the freedom of radial movement of the blades in their slots, they are forced outwardly by the centrifugal force developed by the high speed rotation of the head, the outer bevelled edges of the blades being thereby pressed

outwardly with a force of the proper magnitude to effectively scrape and remove the scale or incrustation from the tube during the advance of the head through the tube, and during the retraction or withdrawal of the head from the tube, the blades produce a burnishing action upon the inside surface of the tube, which closes the pores in the metal and provides it with a smooth finish devoid of pits in which scale forming substances might lodge, thus delaying the subsequent accumulation of scale or incrustation. Each use of the head renders the inside surface of the tube denser, thus reducing the tendency of scale to adhere thereto.

As the disks on the head maintain the outer scraping edges of the blades in parallelism with the inside wall of the tube, maximum scraping capacity is attained by the utilization of the entire length of the blades, which also minimizes the rate of wear of the blades, and furthermore, the ends of the blades cannot gouge into the metal and thus score, striate or otherwise damage the tube.

Although tube cleaning heads constructed in accordance with the present invention may be employed in general for the cleaning of the inner walls of tubes of boilers, heaters, condensers and similar apparatus, they are especially adapted to meet the requirements in the cleaning of the copper tubes of evaporators or other apparatus employed in sugar manufacture, in which the deposits are of a ceramic nature and are hard and dense, the improved cleaning head enabling such scale or incrustation to be removed rapidly and without damaging the relatively soft metal composing the tubes, and imparting to the tubes a burnished or polished surface which inhibits the subsequent accumulation of scale or incrustation.

Since the pressure of the blades against the inside of the tube, during the operation of the cleaning head, is produced solely by the centrifugal force developed in the blades by the rotation of the head, and the action of the blades on the tube is controlled by the disks, the structure of the head is not only simple but the pressure exerted by all of the blades is equal, and lifting or shaving of the metal of the tube is avoided, and moreover, the magnitude of pressure of the blades against the inside of the tube in order to best meet different requirements according to different natures of the scale or incrustation to be removed, and to effect the burnishing of the inside wall of the tube, and to attain the maximum capacity, may be readily varied by appropriately varying the speed of rotation of the head during the cleaning and burnishing operation. As the body and disks and the arrangement of the slots for the blades of the head are symmetrical, these parts of the head are balanced dynamically, and as the blades are held by centrifugal force against the inner surface of the tube being cleaned, there is no objectionable vibration during the operation of the cleaning head.

I claim as my invention:

1. A rotatable tube cleaning head comprising a solid substantially cylindrical body having threaded axial extensions projecting from its ends and formed with radial circumferentially spaced axially extending slots the inner ends of which are closed, a set of balanced blades freely movable radially in said slots solely by centrifugal force during rotation of the head to produce the pressure for removal of incrustations on the inner surface of the tube being cleaned and limited in their inward radial movement by the

closed inner ends of the slots, said blades having straight bevelled outer edges which extend longitudinally of the head, and concentric centering disks rigidly fixed on the respective axial extensions projecting from the ends of the body and engageable by the ends of the blades to limit outward radial movement thereof and to maintain the outer edges of the blades in substantial parallelism with the axis of the head, said disks and the inner ends of the slots providing fixed abutments whereby the outer edges of the blades may lie in inner and outer circles, and said disks being of a diameter greater than the inner but less than the outer circle and engageable with the inner surface of a tube being cleaned to center the head therein and maintain the outer edges of the blades in parallelism with said tube surface and to confine rotation of the outer edges of the blades to paths between said inner and outer circles, said disks having circumferentially spaced recesses in their peripheries for the passage of fluid.

2. A rotatable tube cleaning head comprising a cylindrical body, a plurality of blades symmetrically spaced circumferentially and freely movable radially between inner and outer fixed abutments, said blades having bevelled outer longitudinal edges, and centering disks on the ends of the head concentric with said body and having

circumferentially spaced projections on their peripheries for engagement with the inner surface of a tube to be cleaned, and having recesses between said projections for the passage of fluid, said body and disks being dynamically balanced.

- 5 3. A rotatable tube cleaning head comprising a solid cylindrical body having threaded axial extensions projecting from its ends and formed with radial circumferentially spaced axially extending slots closed at their inner ends, blades movable radially in said slots and having bevelled longitudinal outer edges, a centering disk of greater diameter than said body threaded on one of said axial extensions and cooperative with adjacent ends of the blades to limit their outward radial movement, a sleeve threaded on the other of said axial extensions and cooperative with the other ends of the blades to limit their outward radial movement, and a second centering disk of greater diameter than said body threaded on said other axial extension in locking engagement with said sleeve said disks being of a diameter to maintain the outer bevelled edges of the blades in parallelism with the inner surface of a tube to be cleaned and to limit the outward radial movement of the blades toward said surface of the tube.
